UNITED STATES PATENT OFFICE.

LENOX SIMPSON, OF PITTSBURG, PENNSYLVANIA.

APPARATUS FOR TANNING.

SPECIFICATION forming part of Letters Patent No. 314,199, dated March 17, 1885.

Application filed September 16, 1884. (No model.)

To all whom it may concern:

Be it known that I, LENOX SIMPSON, a citizen of the United States, residing at Pittsburgh, in the county of Allegheny and State of Pennsylvania, have invented certain new and useful Improvements in Apparatus for Tanning, of which the following is a full, clear, and exact description.

The object of my invention is to arrange and connect a system of revolving exhaust tanning-vats, leaching-vats, and supply-tanks in such manner as to economize labor, space, and expense.

The invention consists in the particular arrangement and connection of the vats, tanks, and pumps, as hereinafter more fully set forth.

In the drawings, Figure 1, Sheet 1, represents an end elevation of the improvement; and Fig. 2, Sheet 2, a top plan view of same.

Similar letters of reference indicate corresponding parts throughout the different views.

A represent a series of revolving tanning vats or cylinders, a particular description of which may be found in application marked A, filed of even date herewith.

B B are a series of supply-tanks, situated upon a frame or scaffolding raised at a slight elevation above the cylinders, and connected by flexible pipes with the supply-tubes which enter the hollow necks at one end of said cylinders.

CCare a series of leaching-vats, within which the liquor (of varying degrees of strength) is made. From the bottoms of said vats C extend a series of vertical pipes, D, which are provided with cocks d. Said pipes connect with a pipe, E, extending in front of all the leaching-vats, and having both of its extremities closed. Said pipe is connected with a force-pump, F. By this connection it will be seen that on opening one of the cocks d the liquor from that particular vat, and no other, will be drawn up by the pump. The discharge-pipe of pump F is connected by a branch pipe, f, with a pipe, G, extending along the series of supply-tanks B; said pipe being also closed at either end. Said pipe G is connected by short branch pipes g with each of the supply-tanks, and said branch pipes are each provided with a cock, g'. By this construc-

tion it will be seen that when one of the cocks d and one of the cocks g are opened and the force-pump operated the liquor from the particular leaching-vat over which the cock d lies will be forced into the particular tank with 55 which the open cock g is connected. The object of this construction is as follows: The hides contained in the different cylinders may be of different character and designed for different purposes—as, for instance, one cylinder 60 may contain skins designed to be turned into calf-skin, another into harness-leather, a third into sole-leather, and so on. Each of these different characters of hides requires a different treatment, and consequently must have 65 liquors of different strength. Again, should all the skins be of the same character, yet they may have been placed in the cylinders at different times, and hence also require different strengths of liquor, so that ordinarily it is 70 absolutely indispensable to have liquors of various strengths, and to provide means whereby any strength of liquor may be supplied to any particular supply-tank (and its connected cylinder) without reference to other liquors or 75 cylinders. By my construction this desideratum is met, and the liquor from any leaching-vat (i. e., of any strength) may be pumped into any desired supply-tank. From the discharge end of each of the cylinders a pipe, h, 80 provided with a cock, h', extends to a second pipe, H, which lies above the series of leaching-vats. Each of these pipes H has a branch pipe, h², over each leaching-vat, provided with a cock, h³. By this construction the waste or 85 so-called "exhausted" acid may be emptied into any one of the leaching-vats. It will be understood that in case the cylinder contains leather at various stages in the tanning process the liquor which would be called "exhaust- 90 ed" in one cylinder might be far too strong for another cylinder in which the process had just begun, or which contained tender skins. It is therefore necessary that each cylinder be enabled to empty its exhaust-liquor into any 95 one of the leaching-vats which may be best suited for its reception. Extending upwardly from the discharge-pipes of the cylinders are exhaust-pipes h, which are connected with a pipe, K, extending above the battery of cylinders. 100

ders. Each of these pipes is provided with a cock, k' , by means of which pipe K may be connected with or disconnected from any particular cylinder. Said pipe K is also connected by a pipe, k^2 , with an air-pump, K'. By this construction it will be obvious that the air may be exhausted from any one of the cylinders without affecting the others; or, on the other hand, the air may be exhausted from two or more simultaneously. Again, it may be necessary to revolve one or more or all of the cylinders at the same time. For this purpose the shaft l of one of the triplets of wheels (upon and by which the cylinder turns) of each cylinder is provided with a worm-wheel. A long shaft, L, runs transversely (or at right angles) to said shafts l , which revolve loosely upon said shaft. In juxtaposition to said worms are feathered friction-clutches l' , by means of which the worms may be made secure to the shaft. Operating said clutches are hand-levers L'. By this construction it will be seen that one or more or all of said cylinders may be revolved.

Having thus described my invention, what I claim is—

1. The combination, with supply-vats B, leaching-vats C, and pump F, of the vertical pipes D, having cocks d , the end-closed pipes E, connected with pipes D and pump F, and the end-closed pipe G, the latter being connected by pipe f with the discharge-pipe of said pump, and by cocked pipes g with the supply-tanks B, as and for the purpose specified. 30

2. The combination, with the discharge-pipes of the cylinders A, of the cocked exhaust-pipes k , the pipe K, the air-pump K', and the pipe k^2 , substantially as shown and described. 35

3. In a tanning apparatus of the class described, the combination, with the shaft L, of the shaft l , revolving loosely thereon and provided with a worm-wheel, the feathered friction-clutches l' , and the hand-levers L', substantially as and for the purpose specified. 40 45

LENOX SIMPSON.
